Inventor:

Wesley B. Johnson

By Wilson & McCanna

Attest:

UNITED STATES PATENT OFFICE.

WESLEY B. JOHNSON, OF ROCKFORD, ILLINOIS.

HEELPLATE.

Application filed August 3, 1923. Serial No. 655,550.

To all whom it may concern:

Be it known that I, WESLEY B. JOHNSON, a citizen of the United States, residing at Rockford, in the county of Winnebago and 5 State of Illinois, have invented certain new and useful Improvements in Heel Plates, of which the following is a specification.

This invention pertains in general to boot and shoe making, and has more particular 10 reference to metallic wear plates for heels.

The primary object of my invention is to provide as a new article of manufacture, a top lift, with a heel plate attached, constructed in such novel manner as to constitute 15 a unitary article which may be easily and readily applied to a heel, and which when properly applied will be securely retained on the heel and will greatly increase the life thereof.

20 In furtherance of this object, my invention contemplates the provision of a heel plate built into a top lift and including spurs or the equivalent for permanently securing the plate in connection with the top lift.

25 By reason of this construction the top lift with heel plate combined may be applied as a unit to a heel in the same manner as an ordinary top lift and requires no special skill or additional operation on the part 30 of the shoemaker or repair man in the application.

Another object is to so construct the heel plate in its connection with the top lift as not to impair the degree of fastening 35 between the latter and the heel proper, this being accomplished by providing a nail or peg receiving space between the striking portion and the spur-carrying portion of the plate so that the plate-equipped portion 40 of the top lift may be directly secured to the heel proper in the same manner as any other portion of the top lift.

Still another object is to provide an article of the character described which may be 45 economically produced and marketed and which will serve in a practical and satisfactory manner the purposes intended.

Other objects and attendant advantages 50 will be appreciated by those skilled in this art as the invention becomes better understood by reference to the following description when considered in connection with the accompanying drawings, in which—

55 Figure 1 is a face view of a top lift equipped with a heel plate embodying my invention;

Fig. 2 is a view of the reverse side of the top lift;

Fig. 3 is a side view of a heel equipped 60 with said top lift;

Fig. 4 is a perspective view of the heel plate detached; and

Fig. 5 is a sectional view taken on the line 5—5 of Fig. 2.

In the preferred embodiment of my invention, the heel plate is cast in a single piece of suitable metal, such for example as hard iron. While the shape may be varied, that shown is preferred as being thoroughly practical and serviceable. 65

The plate comprises a curved arcuate striking portion 6 following in contour that of the striking end of the heel and being set into the top lift 7 of the heel, as plainly shown. Said striking portion is preferably 70 of the same depth or thickness as the top lift and presents a narrow striking face 8, which I find is of ample area for all practical purposes and allows as will be presently seen, greater area for the application 75 of nails for securing the top lift to the under lifts.

The striking portion 6 has formed integrally therewith, a narrow fastening portion 9 coplanar with its top portion, joined 80 at the ends 11 to said striking portion, and spaced intermediate its ends therefrom so as to provide an area 12 for the application 85 of nails for securing the top lift to the under lifts. The top lift is cut out to receive the fastening portion, thus leaving 90 the top lift intact, except for the portions cut out to receive the heel plate.

The heel plate is permanently secured to the top lift by means of spurs 13 formed 95 integral with the fastening portion 9 and piercing the top lift, reaching downwardly therethrough and flattened at their points into the face thereof, as plainly shown in Fig. 5. 100

By reason of the foregoing construction, the top lift and heel plate become a unitary structure and constitute an article of manufacture adapted to be applied in the making of a heel the same as an ordinary top lift 105 not equipped with a heel plate.

In applying the top lift, it will be observed that the latter may be secured by nails or pegs to the under lifts in the usual manner and that one or more nails 14 may 110 be passed through the portion 12 for firmly securing the plate-equipped part of said

top lift to said under lifts. It will be observed that when the heel plate is so applied, the fastening portion 9 is confined between adjoining lifts and is permanently secured to the top lift by means of spurs 13. The heel plate is obviously fastened more securely in position by reason of the fact that some of the nails may be passed directly between the striking and fastening portions 6 and 9 respectively, of the plate.

The top lift may obviously be of any suitable material, and the means for fastening such top lift or the equivalent to the heel need not necessarily be nails as other expedients might be employed for this purpose. By building the heel plate into the top lift and securing it thereto by means of spurs or the equivalent, a unitary article as described above, is obtained, which may be sold as a new article of manufacture. This new article obviates the necessity of the shoemaker or repair man fitting the heel plate to the top lift, which operation with the usual type of set-in heel plates requires careful workmanship.

As a result of the present invention, it will be manifest that top lifts in large quantities may be uniformly cut out for the reception of the heel plate by means of proper cutting machines or tools, and that when the heel plate is applied and affixed by clamping the spurs the new article is completed and ready for application to a heel.

It is believed that the foregoing conveys a clear understanding of the objects prefaced above, and while I have illustrated but a single working embodiment it should be understood that various changes might be made in details of construction without departing from the spirit and scope of the invention as expressed in the appended claim.

I claim:

As a new article of manufacture, a top lift for a heel comprising, in combination, a top lift body having flat top and bottom faces and a curved striking end, a metallic heel plate having a striking portion set into the striking end of said body, reaching from said top to the bottom surfaces thereof and conforming to its end curvature, a narrow plate-fastening portion set into the top of said body flush with the top surface thereof, said plate-fastening portion being medially spaced from said striking portion and at its ends joined integrally thereto so as to allow an unobstructed body portion intermediate the striking and fastening portions through which fastening means may be passed through the body for securing it to the under lift of a heel, and spurs integral with said fastening portion at spaced points between its ends extending downwardly therefrom into the body for securing the heel plate thereto.

WESLEY B. JOHNSON.
